PAUL LUCAS, OF FRIEDENAU, NEAR BERLIN, GERMANY.

WICK-VAPORIZER.

1,268,027.

Specification of Letters Patent.

Patented May 28, 1918.

Application filed October 8, 1914. Serial No. 865,711.

To all whom it may concern:

Be it known that I, PAUL LUCAS, a citizen of the German Empire, and residing at Friedenau, near Berlin, Germany, have invented certain new and useful Improvements in Wick-Vaporizers, of which the following is a specification.

My invention relates to improvements in wick vaporizers having wicks composed of cotton or similar organic materials, such as are used for burners of all kinds fed with liquid fuels, and particularly for incandescent paraffin-lamps. In these vaporizers the wick is drawn into the vaporizer tube which is provided above with one or more nozzles and is heated externally by any suitable source of heat, so that the liquid fuel introduced by the wick into the tube and converted into vapor issues from the one or 20 more nozzles at a pressure above atmospheric.

A primary object of my invention is to increase the time which burners provided with such wick vaporizers will burn. To 25 this end I employ a wick of organic material which tightly fills the vaporizer tube and is carbonized to such an extent before being drawn into the tube that when in use it no longer shrinks owing to the vaporizer 30 tube being heated, but snugs closely to the tube even when used for a long period.

Another object of my invention is to increase the strength of a wick of the kind described by making it in an improved manner in order to be able to draw it tightly into the vaporizer tube. To this end I use rope-like cord for the individual threads of the wick. Also, in order to be able to draw the wick in to the tube, the carbonized wick may 40 first be drawn into a thin but strong tubular sleeve.

To these ends my invention consists in the construction, arrangement and combination of parts described hereinafter and 45 pointed out in the claims.

One illustrative embodiment of the invention and a modification thereof are represented by way of example in the accompanying drawing, wherein:

50 Figure 1 is a vertical section through a paraffin burner provided with a wick vaporizer according to my invention, and

Fig. 2 is a like view of part of a similar burner having a modified form of wick.

55 Referring firstly to the burner shown in

Fig. 1 for producing a blue flame, *e. g.* for incandescent paraffin lamps, the fitting 1 in the oil reservoir 2 carries the vaporizer tube 3 tightly filled by the wick 4. This tube 3 is provided at its upper end with a 60 nozzle 5 attached to a stout tubular member 6 which conducts heat well. This member 6 extends upward and is provided near the nozzle 5 with inlets 7 for air and surrounds the mixing tube 8 which carries a 65 piece of wire gauze 9 at its upper end. Projecting into the upper end of the mixing tube 8 is a tube 10 which descends outside to close above the inlets 7 and terminates in an annular burner 11 surrounding the member 6 near the top end of the tube 3. 70

The oil sucked up by the wick 4 is converted in this known kind of burner in the member 6 into vapor owing to the tube 3 being heated by the auxiliary burner 11. 75 The vapor issues at a pressure above atmospheric out of the nozzle 5 and, owing to its energy of flow, carries along with it air entering through the inlets 7 into the mixing tube 8 in which the vapor and air 80 are thoroughly mixed as is necessary for producing the blue flame. This mode of mixing the vapor and air has, as is well known, the advantage that the flame cannot become white, because when the quantity 85 of gas produced is increased, the energy of flow of the gas and with it the quantity of air sucked in increases. Some of the mixed gas and air is conducted back through the tube 10 to the auxiliary burner 11. 90

Heretofore only threads composed of the ordinary cotton of commerce or similar organic materials have been used for the wicks of such wick vaporizers comprising the members 3, 4, 5 and 6. All these materials 95 have the disadvantage, however, that they carbonize under the influence of the heat to which they are subjected, particularly at the place where vaporization takes place. Owing to the carbonization the wick shrinks 100 so that a wick which was previously tight in the vaporizer tube no longer tightly fills the same. The wick therefore no longer presses against the hot tube, whereby the quantity of vapor produced is diminished, while 105 owing to the shrinkage a change of section of the capillary tubes and with it a change in the capillary power of the wick occurs. These defects become noticeable sooner the higher the boiling point of the oil employed. 110

When paraffin is employed, for example, ordinary wicks made of organic materials cannot be used for these reasons.

For obviating these defects, according to my invention I employ a wick consisting of elastic threads of organic substances which tightly fill the vaporizer tube and, before being inserted into the latter, are carbonized to such an extent that the wick no longer shrinks under the action of the heat supplied to the vaporizer. The wick 4 drawn tightly into the tube 3 therefore remains lying tightly against the wall of this tube even after being in use for a long time, so that the heat supplied to the vaporizer always acts in the same manner on the fuel and the capillary power of the wick remains unchanged. Continuity in vaporization and supply of fuel is hereby assured.

Carbonization of the wick before insertion into the vaporizer tube has the additional advantage that the tar products produced in large quantities during carbonization are separated from the wick, and consequently stoppage of the outlet of the nozzle 5 of the vaporizer by such products and the like is prevented. Also, owing to the carbonization a material is produced whose power of absorption is greater than that of the raw material.

Owing to these advantages I attain that incandescent paraffin lamps having wick vaporizers which, when non-carbonized wicks were employed, heretofore burned at most for 60 hours and then gradually extinguished, now burn for more than 2000 hours when the wick vaporizer according to my invention is employed, as has been repeatedly determined by tests. The nozzle does not require to be cleaned nor the wick exchanged.

For freely burning wicks (*i. e.* not for wick vaporizers) it has heretofore been proposed partially to carbonize a wick composed of vegetable substances in order to obtain a whiter flame and to avoid absorption of water. That the sufficiently carbonized wick shall not shrink and that the nozzle shall not become fouled are conditions which are very important in a wick vaporizer, but of no importance at all of course when freely burning wicks are used.

In order that the wick may snug well to the tube it is essential for the threads to be elastic, while on the other hand the threads must have a certain strength in order to be able to be pulled tightly into the vaporizer tube. This strength is greater the lower the temperature at which carbonization takes place. It is consequently advantageous for the temperature of carbonization to be not much higher than that temperature to which the wick is to be subsequently exposed in the vaporizer. When paraffin is employed this temperature is about 275° to

300° C. At this temperature of carbonization not only are too great shrinkage of the fibers and too great loss of material rendering the wick expensive avoided, but the fibers possess sufficient strength and indeed are more elastic than when non-carbonized. The wick therefore has, in spite of its being partially carbonized, a certain elasticity and can be tightly pulled into the vaporizer tube.

Referring now to Fig. 2, the wick 13 tightly pulled into the vaporizer tube 12 is composed of a number of strong twisted cotton strands or cords 14 made in the manner of dressmaker's cord. Each cord 14 consists of a number of strands 15 twisted together and each strand 15 is made of a number of threads 16 twisted together. In consequence of the cotton fibers being repeatedly twisted the strength of the individual fibers and of the entire wick is materially greater than that of loosely wound fibers or of a woven wick. The carbonized wick can therefore be drawn very tightly into the vaporizer tube without breaking, so that the pressure of the fuel in the wick is increased correspondingly.

For this purpose, as shown in dotted lines in Fig. 1, the carbonized wick may be loosely inserted into a thin but strong tubular woven fabric 17 of linen or the like and drawn together with this into the vaporizer. If the tool for drawing the wick in engages the linen fabric the wick itself is compressed solely by lateral forces. As the sleeve 17 must remain in the vaporizer tube it will become carbonized after being in use for a time, but the advantages of the carbonized wick are not materially diminished because the sleeve can be made very thin and nevertheless sufficiently strong.

The invention is also applicable to vaporizer retorts in which packing is used for preventing impulses of gas, because in this case it is necessary for the packing to lie well against the wall of the retort in order to prevent the occurrence of Leidenfrost's phenomenon.

I am aware that it is well known to partially carbonize wicks. This method is used in connection with wicks for ordinary flat or circular burners in which the flame with its root is in immediate contact with the wick and has the object of giving sufficient carbon to whiten the flame. As my invention relates to a different kind of burner, *i. e.* a vapor burner, quite different conditions exist with regard to the wick and therefore the aim of the known process does not come into consideration. According to the present invention the partial carbonizing of the wick has the purpose of obtaining a wick which when forced into a wick tube will not be subjected to shrinkage due to heat applied to the outside of the wick tube and which consequently will remain in close contact

with said tube for a considerable period of use.

I claim:—

1. In a vapor burner the combination with 5 a wick tube, of a nozzle, a Bunsen-burner, means for externally heating said wick and a wick of organic material tightly fitting inside said tube, said wick before being drawn into said tube having been carbonized 10 to such an extent as to resist heat without shrinking and to maintain its original position in close contact with the inner surface of said externally heated tube for a considerable period of use.
- 15 2. In a vapor burner the combination with a wick tube, of a nozzle, a Bunsen-burner means for externally heating said wick tube and a wick of organic material snugly fit-

ting inside said tube, said wick being partially carbonized and consisting of a plurality of cords, each cord being composed of a plurality of twisted strands and each strand comprising a plurality of threads twisted together. 20

3. In a vapor burner, the combination 25 with a tube wick, a nozzle, a Bunsen-burner, a sleeve of woven material adapted to encircle a wick, said sleeve containing the wick adapted to be drawn into the wick tube and into close proximity to the nozzle. 30

In testimony whereof, I affix my signature in the presence of two witnesses.

PAUL LUCAS.
